UNITED STATES PATENT OFFICE

WILLIAM FIELDER AYLES, OF OXHEY, ENGLAND

BLADED HIDE, SKIN, OR LEATHER WORKING MACHINE

Application filed December 7, 1923, Serial No. 679,059, and in Great Britain October 24, 1923.

This invention relates to bladed hide, skin and leather working machines in which pieces of work are operated upon by the edge or edges of a blade or blades and is illustrated 5 as embodied in blades for staking machines.

In prior types of staking machines having reciprocatory staking heads, the blades whatever their form or shape are provided with working edges formed in a continuous line. 10 Such blades, however, do not satisfactorily perform the work for which they are designed, inasmuch as, owing to the almost infinite variety of texture and substance and consequent degrees of firmness, encountered 15 in any one hide or skin, the surface presented to the unbroken working edge of the blade or blades is not as uniform and unyielding as, and therefore not at every point in close contact with, the said edge of the blade or blades 20 so that it cannot possibly be uniformly acted upon throughout the entire area over which the blade passes. In attempts to overcome this defective action of continuous-edged blades, resort has been had to increased working pressure with the result 25 that frequently bursting of the grain surface of the hide or skin and tearing occurs owing to the fact that for some portions of the hide, skin or leather under treatment the pressure and consequent pull are excessive. 30 Loss from this cause is regularly experienced in all leather factories. In blades of general utility in leather working machines, it has hitherto been proposed to notch the operative edge of a convexly curved blade. 35 With such a construction there is danger of damaging any but the toughest hides, skins or leather. Furthermore, the operation of the blade is not uniform throughout its 40 working edge due to sharp differences in contour in closely adjacent portions of the blade.

Accordingly it is an object of the present invention to provide for more equal and uniform treatment of every part of the surface 45 of the hide or skin, and the fundamental

principle upon which the invention is based consists in enabling the hide or skin to adapt itself more closely to the working edge of the blade or blades than is possible with the blades hitherto in use, and without having 50 resort to the excessive pressure hereinbefore mentioned.

This object is attained, in the illustrated construction, by breaking the continuity of the working edge of the blade or blades and 55 creating, by sub-dividing it, a plurality of spaced short working edges in the blade or blades. Such sub-divisions may conveniently be provided by waving, or arching, the said working edge and the waves or arches, 60 thus formed may be of uniform length or they may gradually increase or decrease from the blade centre outwardly. A blade so constructed may be provided with an edge having curved portions the direction of which 65 never diverges more than 45° from parallelism to the longitudinal axis of the blade, thus providing a plurality of work contacting edges to all of which the hide or skin will readily adapt itself, no matter what its texture or substance may be at the several points, 70 so that in passing over the hide or skin, each of these contact points will effectively treat a strip of the hide or skin corresponding in width to the length of the respective sub- 75 division in the working edge of the blade.

Preferably, and as shown, the work contacting edges of the individual blades in a set of blades, are so offset or staggered in relation to each other that the work contacting edges of each blade operate along paths or upon strips in a hide or skin which are between the strips operated upon by the similarly shaped edges of the other blade or blades. 80 Inasmuch as the hide or skin adapts itself 85 readily to the described working edge of the blade or blades relatively little pressure is required to effect operation of the blade or blades on the pieces of work, so that the most important factor producing "burst grain," 90

and waste is eliminated, while the operation itself is more efficiently and speedily performed with less physical and mechanical exertion than with the blades hitherto in use.

5 In the accompanying drawings,—

Fig. 1 shows a blade having a symmetrically waved operating edge.

Fig. 2 shows a blade similar to Fig. 1 in which the projecting work-contacting edges 10 are gradually decreased in length from the center outwardly.

Fig. 3 is a diagrammatic elevation showing the staggered arrangement of the subdivisions of the working edges of two blades 15 of the type disclosed in Fig. 1; and

Fig. 4 is a perspective view of blades of a modified form in which the sub-divisions of the working edges of the blades are arched and arranged in staggered relation so as to 20 work on different strips of the hide or skin.

In the blade 10, which is especially designed for use in staking machines (see Fig. 1 of the drawings), the operative edge of the blade is waved in the plane of the blade, producing 25 reversely curved portions or crests and troughs 12 and 14, respectively, the portions 12 being convexly curved while portions 14 are concavely curved with the edges of the convexly curved portions merging smoothly 30 or gradually, that is, without interruption, into the concavely formed edges. By reason of this construction and arrangement of the reversely curved portions of the blade there is presented to the work a smoothly curved 35 edge throughout the whole length of the blade. Furthermore, the direction of the curved portions never diverges more than 45° from parallelism with the longitudinal axis of the blade. In other words, there is no 40 sharply angular portion, notch, or other abrupt change in the direction of the operative edge of the blade. Because of the continuously smooth unbroken edge of this 45 waved blade, the operations on the work are more uniform than with those blades having sudden changes in the direction of the edge in closely adjacent portions. Moreover, the possibility of damage to the work is reduced to a minimum.

50 While the sub-divisional working edges of the waved type in Fig. 1, are all of uniform length the waved sub-divisional working edges shown in Fig. 2 diminish in length from the centre wave 1 to both sides as at 2.

55 The diagram of Fig. 3 illustrates how the sub-divisional working edges of two blades A and B, by being staggered one in relation to the other, operate upon the whole surface of the hide or skin, the working sub-divisions of blade A, sweeping strips a of the hide or skin, while those of blade B sweep the strips b.

Upon reference to Fig. 4 of the drawings, it will be observed that each of the blades A', B', C', D' has an operative edge provided 65 with arched or convexly curved work treat-

ing portions 16 spaced from each other in the same plane by non-convex portions 18, which preferably and as shown are straight-edged. This is a less expensive blade to manufacture than that disclosed in Fig. 1 of the drawings and is suitable for operations upon heavier pieces of work and upon many different classes of work when the flesh side is presented for the operation of the blade instead of the grain side. In this form of blade 70 also the direction of each convexly curved portion 16 never diverges more than 45° from parallelism to the longitudinal axis of the blade. Preferably, and as shown, blades of the type A', B', C', D' will be used in sets 75 80 with the convexities in staggered relation in adjacent blades, as illustrated in Fig. 4 of the drawings wherein they are shown as operating upon strips, a', b', c', d', of the hide or skin, respectively. As here arranged each 85 of the said strips is worked upon by one blade only, but it may be desirable to work twice over the same strip in which case the sub-divisional working edges of blade C' are arranged to follow in the path of the working edges 90 of blade A' and those of blade D' in the path of those of blade B'—obviously the number of sub-divisions in all the blades will then have to be duplicated. Any number of blades and 95 any desired combination in the relative positions of the sub-divisional working edges in the several blades may be employed, as for example, if in the example shown in Fig. 4 only three blades A', B', D', were provided the sub-divisional working edges of blade A' 100 might be so arranged as to sweep the strips a' and c', while the strips b' and d' are being swept by the blades B' and D' respectively.

Having thus described my invention, what I claim as new and desire to secure by Letters 105 Patent of the United States is:—

1. A scraping blade for use in machines for staking hides, skins, and pieces of leather having, in the plane of the blade, convexly curved portions of substantial convexity in 110 alternation with non-convex portions of substantially the same length as the adjacent convexly curved portions.

2. A scraping blade for use in machines for staking hides, skins, and pieces of leather 115 having, in the plane of the blade, curved portions the direction of which never diverges more than 45° from parallelism to the longitudinal axis of the blade.

3. A scraping blade for use in machines for 120 staking hides, skins and pieces of leather having, in the plane of the blade, a waved edge the adjacent crests and troughs of which merge smoothly into each other and are substantially of equal length.

125 WILLIAM FIELDER AYLES.
